HYDRAULIC OPERATING APPARATUS

Frederick J. Krummel, East St. Louis, Ill., assignor to Walworth Company, Boston, Mass., a corporation of Massachusetts

Application July 14, 1951, Serial No. 236,830

6 Claims. (Cl. 137—567)

1

This invention relates to hydraulic operating apparatus and more particularly to hydraulic operators for valves and the like.

An object of this invention is to control the operated element either from adjacent the element or from a remote location.

Another object of the invention is to apply the component parts of the hydraulic actuator directly to the valve or other operated element.

Another object of the invention is to permit the operated element to be actuated selectively at a rapid rate where excessive force is not required or at a slower rate to reduce the operating effort.

Another object of the invention is to facilitate the changeover from one operating rate to another.

Another object of the invention is to prevent excessive pressure from building up in the actuator.

Another object of the invention is to arrest high velocity in the fluid connections and prevent damage to the operated element.

The foregoing and other objects and advantages are achieved by the hydraulic pump assembly having a cylinder attached to the operated element, such as a conventional valve. The reciprocable stem of the valve is provided with a piston operable in the cylinder under pressure of fluid transferred from a reservoir by operation of a pump. The reservoir is formed by an annular space between the hydraulic cylinder and an outer cylinder. The pump may be attached directly to the operated element adjacent the cylinder or may be located remotely therefrom and connected by suitable fluid lines.

The pump comprises a dual piston arrangement for increasing the speed at which the operated element is moved from one position to another, such as a valve opening operation. Adjustment of a selector device permits only one piston to be operated so that the valve is initially opened with minimum effort. Thereafter, the selector device is readjusted to bring both pistons into operation so that the remaining opening movement is effected at a more rapid rate.

A directional control valve forms part of the pump assembly in a compact arrangement. The control valve may be positioned to direct the fluid under pressure from the pump to one end or the other of the cylinder for operating the piston in both directions. Suitable check valve means are incorporated in the fluid connections to control the operating speed of the operated element. Moreover, sufficient fluid is retained in the reservoir to substantially equal the displacement dif-

2

ference on opposite sides of the piston, due to the valve stem, as visually indicated to the operator.

In the drawings,

5 Fig. 1 is a front elevation, partly in section, of the hydraulic operating device applied to the operated element;

20 Fig. 10 is a partial section of the hydraulic operating device showing a modified form;

Fig. 11 is a schematic view of the hydraulic operating device illustrating the relationship of the fluid passageways, and

25 Fig. 12 is a section taken on the line XII—XII of Fig. 4.

30 Referring more particularly to the drawings, the hydraulic actuator of this invention is shown in Fig. 1 as applied to a conventional rising stem valve, a portion of which is shown as comprising a yoke element 18 having a support cap 12 formed integrally therewith and through which a reciprocable member or valve stem 14 is adapted to project. A recessed stuffing box 15 is provided in the cap 12 for the stem 14. Since conventional valves of this nature may take many forms, further description is deemed unnecessary.

Hydraulic cylinder

35 An hydraulic cylinder 16 is supported at one end on the cap support 12 which is suitably recessed as at 18 for its reception. An outer cylinder 20 is also mounted on the support 12 and is of larger diameter than the cylinder 16 to provide a reservoir 22 in cooperation therewith. As in the case of the hydraulic cylinder 16, the end of the outer cylinder 20 is received within a recess 24 formed in the support 12. Both recesses 18 and 24 may be provided with a suitable packing to prevent leakage from the reservoir 22 and the cylinder 16.

The opposite ends of the cylinders 16 and 20 are mounted within recesses 26 and 28, respectively, formed in a head member 30. Suitable packing may also be employed in the recesses 26, 28 to prevent leakage from this end of the reservoir 22. The head member 30 and the cylinders 16 and 20 are secured rigidly in position on the support 12 by through-bolts 32 which extend longitudinally from the cap member 30 to the support 12 through the reservoir 22.

The reservoir 22 is adapted to contain a quantity of hydraulic fluid, such as oil. The level of this fluid in the reservoir 22 is visible through one or the other of a pair of spaced sight gages 34, 36 which are secured in the wall of the outer cylinder 20 in appropriate locations. An additional sight gage 38 is also secured in the wall of the outer cylinder 20 adjacent support 12 to indicate substantially complete lack of fluid in the reservoir 22. As indicated by the broken lines in Fig. 1, the level of the fluid in the reservoir 22 is visible in the lower sight gage 36 under one condition of operation of the hydraulic operating device as will hereinafter be apparent. Under other conditions of operation the fluid level will be visible in the upper sight gage 34 as will also be apparent hereinafter.

A main piston 40 is secured to the projecting end of the valve stem 14 within the hydraulic cylinder 16. In this instance, the piston 40 and the stem 14 are in threaded engagement and a securing pin 42 is employed between these parts to prevent relative rotation. The support 12 is provided, as shown in Fig. 8, with a transverse passage 44 extending from the outer wall thereof to the recess 15 and communicating with a point within the cylinder 16 on one side of the piston 40. The head 30 is also provided with a transverse passage 46 extending from the outer wall thereof to the central portion and terminating in a restricted orifice 48 extending substantially perpendicular to the passage 46 and communicating with a point within the cylinder 16 on the opposite side of the piston 40. The passage 46 also communicates with a point within the cylinder 16 adjacent the orifice 48 by the provision of an opening 50 having a suitable check valve 52 positioned therein and adapted to close under excess pressure developed within the cylinder 16. Upon such closure of the check valve 52 communication between the passage 46 and the cylinder 16 on the adjacent side of the piston 40 is effected by means of the restricted orifice 48 only.

The passage 46 in the head 30 communicates with a branch passage 54 which extends perpendicularly thereto and overlies the reservoir 22. The branch passage 54 communicates with one end of a tubular member 56 which extends longitudinally through the reservoir 22 to the support 12. The opposite end of the tubular member 56 communicates with a branch passage 58 which extends transversely to the outer wall of the support 12. The arrangement thus provides a pair of passages 44 and 58 communicating with points within the cylinder 16 on either side of the piston 40. The reservoir 22 has an outlet formed by a tubular member 57 which projects for a short distance into the reservoir 22 from the support 12 and communicates with an outlet passage 59 extending transversely to the exterior of the support 12.

Manual pump

The pump and control valve assembly of this invention is jointly contained within a casing 60

which is secured by bolts 62 to the wall of the support 12 overlying the passages 44, 53 and 59. The casing 60 is bored transversely in two places to provide a pair of substantially parallel pump chambers 64. Suitable sealing disks 65 are provided at each end of the chambers 64 which have individual pump pistons 66 mounted for reciprocation in the respective chambers. Such movement of the pump pistons 66 is effected by the provision of rack teeth 68 thereon which operatively engage with a pair of pinions 70, 71 respectively. Pinion 70 is in axial alignment with pinion 71 and has a hollow stem 72 journaled in the casing 60 and projecting therefrom. A cruciform handle socket 74 is secured to the projecting end of the stem 72 for the reception of an operating handle 76 in any one of the four socket arms. Preferably, a locking lug 78 projects from one of the arms of the socket 74 for cooperation with an apertured projection 79 on the casing 60 to receive a padlock or other device for locking the parts in any desired position of operation.

The handle 76 is adapted to be oscillated through an arc set by the toothed portion of the pinions 70, 71 which are consequently rotated in an arcuate path. Provision is made in this invention for rotating both pinions 70, 71 simultaneously or for retaining the pinion 71 stationary while the pinion 70 rotates. Under the latter condition of operation, only the one pump piston 66 associated with the pinion 70 will be reciprocated, as will be apparent, thus reducing the effort required on the operating handle 76. To this end, driving means for the pinions 70, 71 are provided and take the form of a sleeve 75 which is slidable axially of the pinions 70, 71 which are suitably bored for its reception. The sleeve 75 carries a pair of longitudinally aligned key elements 77 which in one position of the sleeve 75 operatively engage with suitable keyways 179 formed in each of the pinions 70, 71 and adapted to register longitudinally one with the other. However, the key elements 77 are positioned sufficiently close together on the sleeve 75 that both may be contained within the one pinion 71 as will appear hereinafter.

The sleeve 75 is mounted on a selector rod 81 which is slidable at one end in the hollow stem 72 and in an apertured projection 23 on the casing 60 at the opposite end. The selector rod 81 is suitably anchored at either end thereof to the sleeve 75 to prevent relative movement. Since the sleeve 75 is shorter in length than the combined pinions 70, 71, it will be apparent that the key elements 77 can be located by slidable movement of the selector rod 81 either in the position shown in Fig. 3 for cooperation with the keyways 179 in both pinions or for cooperation with the single keyway 179 in the pinion 71 only. In the latter event, pinion 70 only will be rotated by operation of the handle 76 since the sleeve 75 and key elements 77 will be ineffective as a driving means in this position of adjustment.

The casing 60 contains a plurality of fluid passageways for conveying fluid from the reservoir 22 to the pump chambers 64 as will now be described. Reference may be had to Fig. 11 for the purpose of tracing the fluid passageways pertinent to this description, but it will be understood that this illustration is schematic only and reference should be had to the remaining figures of the drawing for a proper understanding of the preferred construction.

A pump inlet passage 80 extends through the

casing 60 substantially parallel with the axis of the pump chambers 64 and communicates therewith adjacent the sealing means 65 at either end thereof by means of branch passages 181, 82 at one end of the pump chambers 64 and by means of branch passages 83, 84 at the opposite end thereof. Return of fluid from the chambers 64 through the branch passages 181, 84 to the inlet passage 80 is prevented by the provision of a plurality, in this instance four, check valves 85 positioned one at each junction of these respective passages. The pump inlet passage 80 communicates intermediate its ends with an angular branch passage 88 which in turn, communicates with the outlet passage 59. It is apparent, therefore, that fluid from the reservoir 22 can be introduced to both ends of the pump chambers 64 from the single outlet passage 59.

A second transverse passage 90 extends through the casing 60 substantially parallel with the axis of the pump chambers 64 and spaced from the transverse passage 80. The opposite ends of the transverse passage 90 terminate in two pairs of angular branch passages 91, 92 and 93, 94. The passages 92 and 94 are axially aligned with the branch passages 82 and 84 respectively and communicate therewith. Return of fluid to the pump chambers 64 from the passage 90 is prevented by the provision of a plurality of check valves 96 positioned one at each intersection of the passage 90 and the branch passages 91—93 respectively.

Control valve

As shown in Fig. 3 the control valve of this invention comprises a valve chamber 98 formed in the casing 60 transversely of and in spaced relation to the pump chambers 64. The valve chamber 98 has a bottom wall 100 extending substantially parallel with a portion of angular passage 88 and providing a seat for a disk valve member 102 having a reduced stem 104 spaced from the wall of the chamber 98. An operating stem 106 projects from the reduced stem 104 through the wall of the casing 60 and is provided with a handle 108 by means of which the valve member 102 may be rotated between controlling positions on its seat 100. As indicated in Fig. 2, such rotation occurs through an arc of approximately 180° and the legends "Open" and "Shut" on the casing 60 have reference to the position of the operated element, such as the main valve stem 14 shown in Fig. 1. As will hereinafter be fully apparent, the valve handle 108 may also occupy an intermediate position in which communication is prevented between the reservoir 22 and the hydraulic cylinder 16 under certain alternative modes of operation of the operated element.

The valve chamber 98 is positioned in the casing 60 with reference to the transverse passage 90 so that the chamber 98 intersects the passage 90 intermediate its ends and provides access for fluid into the space in the chamber 98 defined by the reduced stem portion 104. A transverse port 110 is formed in the reduced stem portion 104 and communicates with an eccentric recess 112 formed in the valve member 102 adjacent the valve seat 100. The recess 112 communicates at all times with a connecting passage 114 which connects the valve seat 100 with the passage 88. The recess 112 also communicates with either one of a pair of laterally disposed passages 116, 118 formed in the casing 60 on either side of the passage 114 for communication with the valve seat 100. The passage 116 is axially aligned with

10
15
15
20
20
25
30
35
40
45
50
55

the passage 44 in the support 12. The valve member 102 is provided with an offset port 120 which extends therethrough from the valve seat 100 to the stem 104 substantially parallel with the wall thereof and is adapted to connect the transverse passage 90 with either one of the lateral passages 116, 118 as will hereinafter be apparent.

The valve member 102 is axially apertured between the recess 112 and the port 110 for the reception of a relief valve means in the form of a ball valve member 122 biased by a spring 126 against the wall of the port 110 and being yieldable to permit the escape of fluid thereby under excess pressure and through the passages 114, 88 and 59 to the reservoir 22.

The valve member 102 is biased toward the valve seat 100 by a coil spring 124 mounted on the reduced stem portion 104 and operative between the valve member 102 and an anti-friction bearing 125 (Fig. 3) in which is journaled a portion of the operating stem 106 within the valve chamber 98.

Operation

25 In the operation of the apparatus, fluid is drawn from the reservoir 22 by reciprocation of the pump pistons 66 when operated by the handle 76 through the mechanism described. In a manual closing cycle of the operated element, such as the valve stem 14, the selector rod 81 is positioned to place the sleeve 75 and the key elements 77 in position to cause the pinions 79, 71 to actuate both pistons 66 simultaneously. Under such conditions the parts are in the positions shown 35 in Fig. 3 and the handle 76 may be oscillated to cause the pistons 66 to reciprocate in their respective chambers 64 to intake fluid from the reservoir 22. Since the control valve member 102 will have been placed in "Close" position to connect the recess 112 with the passages 114 and 116, as shown in Fig. 11, then fluid expelled from the pump chambers 66 is transmitted under high pressure through the passages 82, 94 as the case may be and passage 88 into the control valve chamber 98. Such fluid will then pass through the valve port 120, passage 118 and passage 58 in the support 12 to flow through the tubular member 56, passage 64 and passage 46 and enter the hydraulic cylinder 16 above the piston 40 by way of the check valve 59 and restricted orifice 48. The fluid will exert sufficient force upon the piston 40 to move the valve stem 14 in a direction to close the conventional valve being operated. During this cycle, fluid beneath the actuating piston 40 is forced from the space in the hydraulic cylinder 16 through passage 44, passage 116, recess 112, passage 114, passage 88, check valves 86, to the passages 82, 94, 181 and 83 for the pump chambers 64.

60 It should be observed that sufficient fluid is drawn from the reservoir 22 to equalize the displacement difference between the fluid volume above the piston 40 and the volume beneath the piston 40 due and equal to the displacement volume of the operating stem 14 causing the fluid level in the reservoir 22 to be lowered from a level visible in the upper sight gage 34 to a level visible in the lower sight gage 36.

65 In the event that the final closing of the operated element requires excessive manual effort, then the selector rod 81 is repositioned to place the sleeve 75 and key elements 77 in a position where motion of the pinion 79 cannot be transmitted to the pinion 71. Consequently, during oscillation of the handle 76 only the pinion 70

70
75

and its related piston 66 are actuated with reduced effort to intake and expel fluid through the described passages by way of the control valve means 102. Thus, while a similar and sufficient downward force is exerted upon the main piston 40, less manual effort is required than that necessary where both pump pistons 66 move simultaneously.

In moving the operating stem 14 in the opposite direction, that is during a main valve opening cycle, it is probable that undesirable manual effort would initially be required if both pump pistons 66 were actuated simultaneously. Consequently, the selector rod 81 is preferably positioned to place the sleeve 75 in position to register both key elements 77 with the keyway 79 in the single pinion 71. Consequently, oscillation of the handle 76 as described will cause rotation of the pinion 70 only and actuation of its single related pump piston 66.

In this opening cycle, the control valve handle 108 is rotated approximately 180° to oppositely align the control valve port 120 with the passage 116. Hence, the recess 112 connects the passage 114 with passage 118 under these conditions. Thus, fluid under pressure created by the pump piston 66 will flow through the passages 116 and 44 into the hydraulic cylinder 16 beneath the piston 40 to react with sufficient force to open the operated element connected to the operating stem 14. The return of fluid from above the piston 40 will be clear from the foregoing description of the closing operation as will the return of fluid to the reservoir 22 to equalize the displacement difference due and equal to the stem 14. The fluid level rises from the lower sight gage 36 to become visible in the upper sight gage 34.

In this opening cycle, the check valve 50 will close in the event the operating speed becomes greater than desirable. Thus, fluid can flow from the cylinder 16 only through the restricted orifice 48 and an automatic check is provided for arresting high velocity in the opening direction.

During the opening cycle, the operated element such as a conventional valve frequently requires less actuating force after the initial opening is effected. Thus, after an initial opening movement utilizing a single pump piston 66, the selector rod 81 can be repositioned to place the key elements 77 in the position shown in Fig. 3 wherein both pinions 70 and 71 are actuated. Since in such event both pistons 66 will be actuated simultaneously when the handle 76 is operated as described, the remaining amount of movement of the operating stem 14 is effected at an increased speed.

In instances where a source of fluid pressure is available and power operation of the valve in addition to manual operation is desirable, a modified form of apparatus may be utilized. Reference may be had to Fig. 7 wherein a pair of pipe connections 130, 132 is provided in the casing 60 for communication with the passages 116 and 118 respectively. As shown in broken lines, a pair of fluid conveying lines is connected to the pipe connections 130, 132 and to a multi-way valve which in turn is connected to a power driven pump. Prior to such power operation, the control valve member 102 is placed in the intermediate position between "Open" and "Close" as described to isolate the reservoir 22 and the pump chambers 64 from the available source of fluid pressure. As indicated in Fig. 11, the pipe connections 130, 132 bypass the control valve

member 102 and the recess 112 does not register with either passage 116 or 118 in this position.

When the multi-way valve is placed in appropriate position, fluid under pressure is permitted to flow into the pipe connection 130 and passage 116 in the casing 60 to the passage 44 to enter the hydraulic cylinder 16 below the piston 40 and operate the valve stem 14 in a direction to open the conventional valve being operated. During this cycle, fluid above the actuating piston 40 is forced from the space in the hydraulic cylinder 16, passage 58 and passage 118 to the pipe connection 132 and multi-way valve to any suitable reservoir at the available source of fluid pressure.

Closure of the conventional valve being operated through the valve stem 14 is effected upon reversal of the port alignment of the multi-way valve whereupon fluid enters the pipe connection 132, passage 118 and passage 58 to enter the hydraulic cylinder 16 above the piston 40 by way of the check valve 50 and restricted orifice 58. Since the closing operation of the conventional valve has been described in connection with the operation of the manual pump, further description is deemed unnecessary.

A further modified form of device is shown in Fig. 10 wherein a main piston 134 is provided with a cylindrical extension 136 which is co-operable with the wall of a hollow projection 138 formed on the support 140. The passage 44 in this embodiment is formed in the support 140 and communicates by way of a restricted opening 142 with the interior of the projection 138 beneath the extension 136. Since a slight clearance exists between the extension 136 and the wall of the projection 138, fluid in the cylinder 16 beneath the piston 134 will create a dash-pot effect and serve to cushion the conventional valve being operated by the valve stem 14 during its final closing movement.

It will be apparent that the pump and control valve assembly of this invention could be located at a remote point from the operated device and connected to the support by suitable pipes to transmit fluid pressure to the hydraulic actuator. These and other changes could be made in the arrangement of parts and in the details of construction within the scope of the appended claims.

I claim:

1. Pumping means comprising in combination, a casing providing a pair of cylinders, a pair of pistons reciprocably mounted in said cylinders respectively, each end of each piston forming with the adjacent walls of its associated cylinder a pressure generating chamber, means defining a pair of racks each operatively associated with one of said pistons respectively, pinion means rotatable in said casing and engageable with said racks for reciprocating said pistons, manually operable actuating means, a driving element between said actuating means and said pinion means for transmitting torque therebetween, said element having a first position wherein in said actuating means is operatively connected to both of said pistons and a second position wherein said actuating means is operatively connected to a selected one of said pistons, manually operable means for moving said element between said positions, and means for passing fluid under pressure from said chambers upon reciprocation of said pistons.

2. Pumping means as claimed in claim 1 wherein in said pinion means includes a pair of pinions

meshing respectively with said racks, said driving element being connected to both of said pinions in said first position and to a selected one of said pinions in said second position.

3. Hydraulic operating means for a fluid motor comprising a casing having at least one pump chamber therein, pumping means in said chamber, manually operable means for actuating said pumping means, a first passage in said casing communicating with said chamber and adapted to be connected to one source of fluid under pressure, a valve chamber in said casing, second and third passages in said casing communicating with said valve chamber and adapted to be connected to the fluid motor, a fourth passage in said casing for conveying fluid discharged by said pumping means to said valve chamber, control valve means in said valve chamber having a first position wherein said fourth passage communicates with said second passage, a second position wherein said fourth passage communicates with the said third passage, and a third position wherein communication between said fourth passage and said second and third passages is prevented, means for moving said control valve between said positions, and a pair of auxiliary passages in said casing communicating with said second and third passages respectively and adapted to be connected to a second source of fluid under pressure.

4. Pumping means comprising in combination, a casing providing a pair of cylinders, a pair of pistons reciprocably mounted in said cylinders respectively, each end of each piston forming with the adjacent walls of its associated cylinder a pressure generating chamber, means for passing fluid under pressure from said chambers upon reciprocation of said pistons, means defining a pair of racks each operatively associated with one of said pistons respectively, a pair of axially aligned pinions in said casing and engageable respectively with said racks, and driving means engageable with said pinions for reciprocating said pistons, said driving means including an element slidable axially relative to said pinions and having a first position wherein said driving means is operatively connected to both of said pinions and a second position wherein said driving means is operatively connected to a selected one of said pinions.

5. Pumping means as claimed in claim 4 wherein in said axially aligned pinions have hollow walls for reception of said slidable element therein, and interengaging means on said hollow walls and said element operable in said first position of said element on both of said pinions and being disengaged from said selected one of said pinions in said second position.

6. Pumping means comprising in combination, 10 a casing having a pair of substantially parallel cylinders therein, a pair of pistons reciprocably mounted in said cylinders respectively, each end of each piston forming with the adjacent walls of its associated cylinder a pressure generating chamber, means for passing fluid under pressure from said chamber upon reciprocation of said pistons, said pistons each having a rack formed on the side wall thereof, a pair of axially aligned hollow pinions extending transversely of said pistons and meshing respectively with said racks, 15 a hollow stem on one of said pinions and extending exteriorly of said casing, manual operating means carried by said stem for rotating said one pinion, a slidable element extending through said stem and said pinions and accessible exteriorly of said casing, and interengaging means on said pinions and said slidable element operative in one position of the latter for connecting both pinions to said operating means and in another 20 position for connecting said one pinion only to said operating means.
